UNITED STATES PATENT OFFICE.

AZEL CLARENCE HOUGH, OF JANESVILLE, WISCONSIN, ASSIGNEE TO HOUGH SHADE CORPORATION, OF JANESVILLE, WISCONSIN, A CORPORATION OF CONNECTICUT.

SCREEN, SHADE, AND THE LIKE.

1,238,064.

Specification of Letters Patent. Patented Aug. 21, 1917.

Application filed February 10, 1917. Serial No. 147,790.

To all whom it may concern:

Be it known that I, AZEL CLARENCE HOUGH, a citizen of the United States, and resident of Janesville, county of Rock, and 5 State of Wisconsin, have invented an Improvement in Screens, Shades, and the like, of which the following description, in connection with the accompanying drawings, is a specification, like letters on the drawings 10 representing like parts.

My present invention relates to the manufacture of screens, shades, and the like, having a construction permitting ventilation therethrough and constitutes a divisional 15 application of my prior application, Ser. No. 87,854, filed March 28, 1916. In said prior application I have illustrated my novel ventilating screen and have claimed the same broadly, and in the present application 20 I describe, illustrate and claim modifications of ventilating constructions, which may be employed in woven screens, shades or the like. The advantages and importance of a ventilating screen, or a screen or shade 25 having a ventilating portion or portions, will be readily appreciated, and are described in my said prior application. Such a ventilating section in a woven screen must have suitable provision for securing the 30 spaced relation between the slats forming the screen and the warp strands or cords holding them together, while also retaining the warp strands or cords interlaced with sufficient tension to hold, tightly, the slats 35 and prevent "end chase" or displacement of the slats. In my said prior application, of which the present is a divisional and a continuation, I have shown two methods which are practical, one the twisting of the warp 40 strands or cords between adjacent slats to space the same and yet to hold said slats firmly engaged and interlaced by the warp strands, which form is claimed both broadly and specifically in said prior case;—and the 45 construction of the ventilating section formed of relatively thick slats, so that, although the warp cords are woven tightly thereabout, the length of the cords between adjacent slats, owing to said thickness, will 50 permit a separation of the slats when the shade is suspended and in use. In the present application I intend to claim the latter construction of thick slats and other modifications of ventilating shade constructions. For example, said slats may be of consider-

able weight so as to separate when suspended, or may be held spaced by short sleeves, buttons or the like. All such devices, it will be understood, must permit the shade to be readily wound, withstand rough 60 handling, wind pressure, etc., and yet embody a woven fabric structure. Further modifications will also readily occur to those skilled in the art, and therefore I do not intend to be limited specifically to the details 65 herein shown, but believe that I am entitled to claim equivalent constructions, as defined by the appended claims.

In the actual manufacture of woven screens or shades having a ventilating portion, I find it desirable to employ relatively broad slats for the non-ventilating portion and comparatively narrow slats for the ventilating portion or portions. This combination of broad slats for one section 70 and narrow for the spaced portions, affording special features and advantages in a woven fabric of this kind, and I therefore wish to claim this particular combination as a feature of my woven screen combining 75 ventilating and non-ventilating sections.

Further features of the invention, details of construction, and novel combinations of parts will be hereinafter more fully pointed out and claimed.

Figure 1 is a side view of a portion of my ventilating screen showing several modifications of ventilating constructions, in combination with a non-ventilating section 80 of the screen;

Fig. 2 is a view in cross section along the line 2—2 of Fig. 1, and Fig. 3 is an enlarged cross sectional view showing one method of separating the ventilating slats in detail.

It will be understood that the drawings 95 are illustrative merely, and do not purport to show an actual commercial ventilating screen with the different methods of securing ventilating, nor the respective positions throughout the screen, of the ventilating section. In actual practice it will be customary to have only one type of ventilating construction in the same screen and it will also be probably customary to provide such ventilating section either at the extreme top 100 portion or near the extreme bottom portion, or at or near both top and bottom of the screen. Such arrangement enables the non-ventilating screen portion to constitute the greater area and the ventilating portions, at 110

the extreme top or the extreme bottom or at both top and bottom, will be in the respective positions for best service in admitting air currents to pass therethrough, while 5 also in position to be unobjectionable in admitting the sun's rays.

Referring to the drawings, my invention comprises a shade or screen having a plurality of transverse slats 1, preferably of 10 wood, fiber or the like, and of substantial width, held in a flexible yet firm and rigid manner by a tightly woven series of warp cords or strands 2 and 3 tightly interlaced thereabout at spaced intervals throughout 15 the length of the slats. Retaining strips 4 and 5 strengthen the screen at the top or at suitable intervals and also serve to bind the warp cords firmly and prevent loosening of the same, while permitting flexibility 20 throughout the entire fabric structure to allow it to be rolled up.

The ventilating portion or portions preferably comprise a plurality of relatively narrow slats which may be of different sizes 25 in cross section, or of different weight, as will be explained. In the particular form of ventilating section illustrated by the slat members 6, 7 and 8, the said members are relatively thick, being nearly square in 30 cross section, or at least sufficiently thick so that the length of the warp cords 2 and 3, as the same are interlaced during the weaving in the process of manufacture of the entire screen fabric, provide such a length of 35 cord extending crosswise between the adjacent slat members as to permit sufficient stretch or yield,—no matter how tightly beaten up the slats and tightly woven the warp strands may be, as to permit a substantial 40 separation of the slat members when the screen is suspended or the fabric stretched out. A similar construction is shown in the relatively thick slat members 45 9 and 10 showing how the warp cords 2 and 3 will necessarily permit a substantial spacing or separation of adjacent thick slats, thus providing ventilating spaces between them. In the particular form shown in the slats 6, 7 and 8, however, I prefer to affix a 50 separating element, which will hold these slats in a predetermined spaced position, while still permitting the flexibility and rolling capacity of the entire screen and also tightly binding the warp cords about the slat members so as to hold them firmly and 55 prevent the slats from becoming loose, thus eliminating "end chase." Such binding and spacing members are shown at 11, 12, 13 and 14, being illustrated in enlarged view in 60 Fig. 3. These members are clasped or otherwise affixed about the warp strands 2 and 3 between these slats and thereby serve to hold the same in an exact spaced relation, as well as holding the fabric firmly and retaining all the slats in proper alinement. 65

These spacing and retaining members may be of any suitable material, and are preferably made as small rings or sleeves of metal, celluloid, fiber or fabric, clasped about and firmly binding the warp cords. In this construction, the ventilating slats, whether wide or narrow, are held as firmly spaced from each other as in the method shown in my prior application, wherein the warp strands are firmly twisted about each other one or 70 more times between adjacent slats to constitute a ventilating section, both constructions being adapted to the woven type of screen and retaining the flexibility of the fabric, together with a spacing of the slats wherever 75 desired to afford ventilation. In the form illustrated with the slats 9 and 10 the spacing is secured through suspension of the fabric when in use, by the separation of the slats owing to the relative thickness thereof, 80 identically as shown in the modifications of 85 Figs. 5 and 6 in my prior application, Ser. No. 87,354.

A further modification of ventilating construction is illustrated in the arrangement 90 of slat members 15, 16 and 17, which slat members may be either of the same thickness as the non-ventilating members 1, or of greater thickness, such as that of the slat members 6 to 10. These slats 15, 16 and 17, 95 however, depend upon their weight to secure a spacing or opening when the screen is suspended and in use in order to attain the ventilating desired. It will be readily appreciated that a suitable increased weight 100 in the slats will cause the spacing, as well as an increased thickness and although this particular modification is scarcely feasible, because it is important to have the entire screen of relatively light weight, yet I intend the scope of certain of the appended 105 claims to cover this form also.

At any point desired throughout the extent of the fabric, I may apply reinforcing strips or members 20, 20, similar to the 110 members 4 and 5, which will aid in binding the warp cords 2 and 3 and prevent the working or loosening of the warp strands throughout their length.

While I have shown the spacing and binding sleeves or members 12, 13 and 14 in position about the relatively thick slats 6, 7 and 8, it will be appreciated that these spacing members may be utilized between slats of equal thickness to that of the main slat 120 members 1, in which instance the entire fabric could be made of the same sized slats, so far as thickness is concerned.

The various modifications herein described, while not as efficient and desirable 125 as the method of twisting the warp strands, are nevertheless equivalent constructions in so far as the broad idea of securing a ventilating portion in a woven screen is concerned, and therefore may be considered as 130

coming under the broader claims of said prior application.

Also the particular feature of having the relatively broad slats for the non-ventilating portion and the narrow slats, irrespective of their thickness or weight, for the ventilating portion, has proven to be a feature of particular importance in the construction of a ventilating screen and although shown in my said prior application, it is hereby elected to claim the same in the present case.

My invention is further described and defined in the form of claims as follows.

1. A woven screen of the kind described, comprising a plurality of transverse slats closely held together by woven warp-strands, in combination with a plurality of transverse slats of greater thickness than said closely woven slats, whereby the latter will be spaced from each other when suspended, to provide a ventilating section in the screen.

2. A woven screen of the kind described, comprising a plurality of transverse slats closely held together by woven warp-strands,

in combination with a plurality of transverse slats of greater thickness than said closely woven slats held together with the same weave, whereby the latter will be spaced from each other when suspended, to provide a ventilating section in the screen.

3. A woven screen of the kind described, comprising a ventilating portion and a non-ventilating portion, said non-ventilating portion consisting in slats held closely together by woven warp strands interlaced thereabout, said ventilating portion having the slats of greater thickness than those of said non-ventilating portion and so woven by said warp strands as to permit the said thick slats to be spaced from each other and from the end slat of the non-ventilating portion.

In testimony whereof, I have signed my name to this specification, in the presence of two subscribing witnesses.

AZEL CLARENCE HOUGH.
